UNITED STATES PATENT OFFICE.

ALBERT H. EHRLICH, OF ST. JOSEPH, MISSOURI.

DESIGN FOR A LOCK-CASING AND HANDLE.

50,376.

Specification for Design.

Patented Feb. 27, 1917.

Application filed December 9, 1915. Serial No. 66,018. Term of patent 7 years.

To all whom it may concern:

Be it known that I, ALBERT H. EHRLICH, a citizen of the United States, residing at St. Joseph, in the county of Buchanan, State of Missouri, have invented a new, original, and ornamental Design for a Lock-Casing and Handle, of which the following is a specification, reference being had to the accompanying drawing, forming part thereof.

Figure 1 is a perspective view of my design for a lock-casing and handle.

Fig. 2 is an end view of the casing and handle.

I claim:

The ornamental design for a lock-casing and handle, as shown.

ALBERT H. EHRLICH.
